UNITED STATES PATENT OFFICE.

CHARLES J. HOFFMAN AND ROBERT S. SHRADER, OF INDIANAPOLIS, INDIANA.

BRIDGE GOLF.

Application filed September 15, 1928. Serial No. 306,180.

This invention relates to a new article of manufacture for use in playing a game of skill.

The game, as will be hereinafter more fully described, employs in the playing thereof a number of bridges, and it is the object of this invention to construct and form said bridges as and for the purposes more fully set forth in the accompanying drawings and 10 specifications.

The full nature of the invention will be more fully understood from the accompanying drawings and the following description and claims:

15 In the drawings Fig. 1 is a front elevation of a bridge mounted in position. Fig. 2 is a side elevation thereof. Fig. 3 is a diagonal illustration of the arrangement of the bridges in playing the game of skill.

20 In the drawings there is shown a bridge comprising a U-shaped wire staple 10 having downwardly extending pointed free ends indicated at 11 adapted to be inserted in the ground. Secured to and supported by the 25 upper rounded portion of the staple there is a sheet metal shield 12 having its edges formed about the staple for securing it thereto. Said shield terminates in a straight horizontal line to provide a bottom edge 13 and is formed 30 with an opening 14 spaced equi-distant from the sides thereof and extending upwardly from the bottom edge slightly less than half way to the top portion thereof. Said opening has the top thereof rounded to substantially 35 correspond with the curved top of the staple and extends in width approximately one-third of the width of said staple.

40 For the purpose herein employed, the staple is approximately nine inches in width and fourteen inches in height. The bottom edge of the shield 12 extends approximately six inches above the lower ends of the staple and the opening 14 in said shield extends substantially four and one-half inches above the 45 lower edge 13. Said opening is three inches in width and is spaced three inches from either side of the shield.

50 As shown in Fig. 3, the game is played by inserting the bridges formed by the staples and shields 12 in the ground in alignment with each other and spaced an equi-distance apart. They may be spaced apart at any distance, depending upon the size of the lawn on which the game is to be played.

55 The first player places his ball 15, such as a golf ball, in direct line with the bridge

indicated by the numeral 1 at a distance of substantially three feet. The ball is then driven through the bridge 1 as indicated by dotted lines in the direction of the arrow, 60 which may be done with a club such as a golf putter. The ball may be driven through the bridge in one stroke, but if the ball fails to go through it is laid aside to let the second player attempt to putt the ball through the 65 first bridge. Whereupon the first player replaces his ball preparatory for his next stroke. After driving the balls through the first bridge from the side indicated by the numeral 1, they are driven down the field 70 near the opposite end and returned through that side of the bridge indicated by 1'. They are continued to be driven through the bridges in their successive numerical order as indicated upon their opposite faces. For instance, the first bridge has the numeral 1 on one side and the numeral 9' on the other side, whereas the last bridge has the numeral 9 on the one side and the numeral 1' on the other side. Considering the bridges by the 75 numbers used on the opposite sides thereof, the ball is driven through bridge No. 1, back through bridge 2', through bridge 3' back through bridge 4', through bridge 5 back through bridge 6', through bridge 7 back through bridge 8' and through bridge 9, 80 which completes the first 9 bridges. The game is then repeated for the second nine, starting in the reverse order through bridge 1', back through bridge 2, etc. It is the object of the game to make the nine bridges in the least number of strokes. 85

90 In positioning the bridges, the lower edge 13 of the shield is caused to extend above the ground just sufficiently to freely permit the 95 passage of the ball thereunder but prevent the passage of the ball if it bounces to any extent upon reaching the bridge. The width of the opening 14 is such as to freely permit the ball to pass therethrough, whereby the player 100 is given the incentive to endeavor to cause the ball to pass centrally of the bridge so that he will not be penalized if it bounces upon reaching the bridge. 105

The invention claimed is:

110 1. As a new article of manufacture, a bridge for use in a game of skill under which a ball must be passed, said bridge comprising a wire support bent U-shaped adapted to have its free ends extend into the ground, and a sheet metal shield secured to the upper portion of said support and having its lower

edge spaced from the ground a sufficient distance to permit said ball to pass thereunder, said shield being provided with a central aperture formed in the lower edge thereof and 5 extending thereabove of sufficient width to permit said ball to pass between the side edges thereof.

2. As a new article of manufacture, a bridge for use in a game of skill under which 10 a ball must be passed, said bridge comprising a wire support bent U-shaped with its

free ends adapted to extend into the ground, and a shield mounted on said support and spaced from the ground for permitting said ball to pass thereunder, said shield being provided with an aperture adapted to permit the ball to pass therethrough provided it is directed centrally thereof. 15

In witness whereof, we have hereunto affixed our signatures.

ROBERT S. SHRADER.
CHARLES J. HOFFMAN.
